UNITED STATES PATENT OFFICE.

ERNST H. ELZEMEYER AND PAUL S. KNITTEL, OF ST. LOUIS, MISSOURI; MINNIE ELZEMEYER EXECUTRIX OF SAID ERNST H. ELZEMEYER, DECEASED.

FURNACE.

Application filed July 5, 1923. Serial No. 649,568.

Our invention relates to furnaces and particularly to a chamber that is adapted for burning pulverized fuel or diffused oil and gas, or a combination of these fuels; and it 5 has for its principal object a construction in which the walls are kept relatively cool, in which all of the fuel is consumed and in which the slag and ashes are easily disposed of.

The invention consists principally in providing the furnace with walls of porous or 10 spongy brick or the like in which the usual draft openings are omitted and in providing the combustion chamber with a sloping floor. The invention further consists in the furnace 15 and in the parts and combinations of parts hereinafter described and claimed.

In the accompanying drawing,

Fig. 1 is a vertical section of a furnace embodying our invention,

20 Fig. 2 is a horizontal section,

Fig. 3 is a section of a portion of the double wall under the boiler, and

25 Fig. 4 is a detail view of one of the bricks forming the walls.

Mounted on suitable supports 1 of iron or other material that rest on suitable foundation members 2 are tiles 3. The tiles 3 are preferably overlaid with a covering 4 of firebrick. The supports 1 are considerably inclined, so that the floor slopes downwardly 30 from the back of the furnace to the front.

The furnace has a front wall 5 which may be curved as shown in the drawing, or of any other suitable shape and side walls 6. The 35 front and side walls may be made of firebrick or the like or may be of monolithic construction, composed of fireclay and other suitable materials to give a porous construction.

The back wall 7 of the furnace is made of 40 any suitable construction and supporting walls 8 extend therefrom along the side walls 6 underneath the boiler tubes 9 that are supported thereabove in any suitable manner. Preferably the outer walls 8 are spaced away 45 from the inner walls 6 and are connected at the end with the front wall.

The furnace is provided with a suitable roof, 10 that is preferably made of firebrick or the like. The side walls 6 are provided 50 with vertically disposed reinforcing rods 11 that strengthen them and prevent them from buckling. Secured to these rods at intervals are stay members 12 that extend through the space between the inner and outer walls 55 and are bent against the face of the outer

wall 8. Preferably the stays 12 are provided with rebent portions 13 that lie against the inner face of the outer wall and the opposing face of the inner wall. These stays give additional strength to the inner wall and prevent it from buckling.

Extending through an opening in the roof of the furnace is a suitable burner 14 that is adapted to burn pulverized fuel or diffused oil and gas or a mixture of these fuels. The 65 burner may be of the kind shown in our Patent No. 1,449,169 dated March 20, 1923, for apparatus for producing, separating and feeding powdered coal, or in our copending application Ser. No. 648,402 filed June 28, 70 1923, for apparatus for mixing and feeding pulverized fuel, gas and oil. The fuel that passes in the furnace is deficient in oxygen, so that air is drawn into the furnace through the front and side walls and also through the 75 floor. The usual draft openings are omitted; so that the air filters through the walls and floor at all points, thus tending to keep the walls and floor cool and also giving an even draft throughout the furnace. As has been 80 stated the walls and floor are of porous or spongy material to permit filtration of air therethrough. The smaller particles of fuel and the gases are ignited by any suitable means such as a pilot light (not shown in the 85 drawing). As soon as they leave the burner tube, the burning fuel particles spread out into a fan-shaped flame as indicated in Fig. 2 of the drawing, the flame extending toward the back of the furnace in the direction of the 90 draft. The heavier particles that are not ignited, strike the sloping floor and rebound upwardly and toward the front of the furnace, on account of the slope of the floor as indicated in Fig. 2. The draft carries these particles into the path of the flame again, so that 95 all particles of the fuel are consumed. Any particles that are too heavy to be carried back into the main flame will be consumed near the floor, the air filtering through the tile and brick of the floor supplying oxygen and also furnishing a draft to carry the fuel particles upwardly and to cool the slag and ashes.

The ashes and slag roll down the sloping 105 floor and accumulate near the front of the furnace. An opening 15 is provided at the bottom of the front wall of the furnace which is normally partly closed by a vertically sliding door 16. The door is preferably sus-

pended on a cord 17 that passes over suitable pulleys 18 and at the end of which is mounted a counterweight 19 for the door. The counterweight is provided with a projecting iron portion 20 that extends into a solenoid coil 21 that is connected with the terminals of a meter 22 that indicates the amount of carbon-dioxide in the combustion chamber. When this passes the desired quantity, the meter 10 closes the circuit through the coil, thus attracting the projecting member of the counterweight and causing the door to be raised. This permits the escape of ashes and slag and the entry of air to reduce the proportion of 15 carbon-dioxide.

The hottest spot of the flame is located underneath the mouth of the burner tube a short distance below the roof. The air entering the combustion chamber around the burner cools 20 and protects the roof against this hot spot. The fuel particles are driven toward the floor as above described. The air filtering through the walls creates a draft away from the walls and thus prevents the flame from spreading 25 to the walls. Thus the walls are protected from the flame and the highest temperature is maintained where it will be most effective in heating the boiler tubes. As the heat is increased, the walls become more porous and 30 larger quantities of air can filter through, thus cooling the wall. If more fuel is fed into the chamber, the draft is increased thus increasing the amount of air that filters through the walls, and giving the flame sufficient oxygen. A certain amount of air flows in through 35 the ash hole and assists in forcing the light unconsumed fuel particles back into the flame.

The herein described furnace has numerous 40 advantages. It prevents the walls of the furnace from being overheated and thus prolongs their life. It accomplishes complete combustion of all particles of the fuel and

thus is economical in operation. It directs the heat of the flame away from the walls and 45 toward the boiler tubes where it will be most effective.

Obviously, the invention is not limited to the details of construction hereinbefore described and illustrated, and we do not wish 50 to be limited to the precise construction shown.

What we claim is:

1. A furnace comprising side and end walls, a roof, a burner projecting through said roof, a sloping floor, said walls and floor being of porous material to permit air to filter therethrough and being otherwise free from draft openings, and an ash gate at the bottom of the end wall and sloping floor. 55

2. A furnace comprising side and end walls, a roof, a burner projecting through said roof, a sloping floor, an ash gate at the bottom of the end wall and sloping floor, a meter for measuring the amount of carbon-dioxide in the combustion chamber and means controlled by said meter for raising and lowering said ash gate. 60

3. A furnace comprising side and end walls, a roof, a burner projecting through said roof, and a sloping floor, said walls and floor being of porous material to permit air to filter therethrough and being otherwise free from draft openings. 70

4. A furnace comprising side and end walls, a roof, a floor steeply sloping from the back to the front of the furnace, a burner projecting through said roof, an ash gate at the bottom of the floor and end wall, said gate being normally closed and means controlled by the amount of carbon-dioxide in the furnace for opening said gate. 75

Signed at St. Louis, Missouri, this 30th day of June, 1923.

ERNST H. ELZEMEYER.
PAUL S. KNITTEL.
